(57) **CLAIM**

The ornamental design for a wristwatch body, as shown and described.

DESCRIPTION

FIG. 1 is a front elevation view of a wristwatch body showing my design;

FIG. 2 is a rear elevation view of the wristwatch body;

FIG. 3 is a left side elevation view of the wristwatch body;

FIG. 4 is a right side elevation view of the wristwatch body;

FIG. 5 is a top plan view of the wristwatch body;

FIG. 6 is a bottom plan view of the wristwatch body;

FIG. 7 is a perspective view of the wristwatch body; and,

FIG. 8 is a front elevation view of the wristwatch body and a wristwatch strap presented in broken lines.

Throughout the Figures, broken lines are included for the purpose of illustrating environment of the design and form no part of the claimed design.
